United States Patent Office.

MERRITT F. POTTER, OF KANEVILLE, ILLINOIS.

Letters Patent No. 91,481, dated June 15, 1869.

IMPROVEMENT IN MILK-COOLERS.

The Schedule referred to in these Letters Patent and making part of the same.

To all whom it may concern:

Be it known that I, MERRITT F. POTTER, of Kaneville, in the county of Kane, and State of Illinois, have invented a new and useful Improvement in Milk-Coolers; and I do hereby declare the following to be a full and exact description of the construction and operation of the same, reference being had to the annexed drawings, making a part of this specification, of which—

Figure 1 is a perspective view, and

Figure 2, a vertical section.

My invention consists in the method by which I conduct cold water upward into a can or other vessel containing milk, or other liquid to be cooled, and return it from within the can down again, from the platform on which the can is standing, automatically, without the labor of carrying it by hand; and also in a vessel which spreads the cooling-liquid into a thin sheet, thereby greatly economizing the amount of water used.

To enable others to make and use my invention, I will proceed to describe its construction and operation.

A represents an annular cylindrical vessel, open at the top and bottom. It may be made of sheet-metal, tin being a good metal of which to make it.

The inner or concave surface of this cylinder is surrounded by spiral wire c, of about one-eighth inch diameter. This spiral wire is soldered to the inner wall. Outside this wire, and closely adherent to it, the outer or convex wall of the cylinder is fastened and soldered tight. This spiral wire forms a circuitous channel or passage for the water. This passage has a thickness only equal to the diameter of the spiral wire, and is intended to be about one-eighth of an inch in thickness. The inner and outer coating of this cylinder are soldered together, a small burr being formed upon the inner casing at the top and bottom. This spiral wire adds greatly to the strength of the cylinder, and keeps the passage, for the liquid running through it, of a uniform calibre.

Fig. 1 shows a perspective view of the cooling-cylinder A, which is to spread the water into a thin spiral sheet, and which I shall henceforth call a spreading-cylinder or spreading-chamber.

Fig. 1 shows a perspective view of the spreading-chamber A standing in a milk-can, J, ready for use.

Fig. 2 represents a vertical section of the spreading-chamber A, standing by itself.

W represents the thin spiral channel, along which the water is conducted in a thin sheet several times around the spreading-chamber.

n are small legs, which support the spreading-chamber above the bottom of the can, and allow the milk to circulate beneath it.

e are several openings in the walls of the spreading-chamber, to allow the milk to pass freely from outside to inside of the chamber, and thus preserve an even temperature of the whole.

To the inside of the spreading-chamber A, the vertical tube B is soldered.

At the upper end of the tube B is an elbow, with a short horizontal projection of the tube extending out four or five inches beyond the outer wall of the spreading-chamber.

At the bottom of the tube B, an opening, D, is seen through the inner wall of the spreading-chamber.

This opening connects the cavity of the tube B with that of the spiral channel W.

F is a tube, attached by its upper end to the tube B by an air-tight joint.

The other end of this tube is set in a tub, H, standing about two feet above the surface of the ground.

Another tube, G, some longer than F, is also fitted, by an air-tight joint, to the short tube S.

The other end is set in a low trough near the ground, and lower than the level of the tub H.

The great difficulty in cooling milk before carrying it to a cheese-factory, is owing to the labor of carrying the water up above the level of the can, to form a reservoir, from which the water could be brought in contact with the milk, for the cans have to be placed upon an elevated platform before they are filled, to facilitate their loading into the wagon.

By my method, a great part of this labor is avoided, and the milk is all cooled in the most rapid manner, with the least possible consumption of water, as I will now proceed to show.

Suppose the can J is standing on the platform filled with warm milk, in which the spreading-chamber A is seen standing.

I first fill the tub H with cold water. In this water I immerse the lower end of the pipe F.

It will be more convenient if this pipe should be provided with a valve, though this is not essential. It would be more convenient also if these tubes were made flexible, though metal ones could be used.

Having immersed the lower end of pipe F, I proceed to exhaust the air from the lower end of tube G.

This can be readily done by a small suction-pump, easily attached to the pipe G.

As fast as the air becomes exhausted, the water will flow from tub H along the pipe F, up into the tube B, downward along B into the bottom of the spreading-chamber A, upward along the spiral channel W to the pipe S, into the pipe G, down which it flows, and is discharged at the trough L warm.

The rapidity of the flow can be controlled by the stop-cock where it is discharged.

It will be observed in my cooler, that all the cooling-surfaces are vertical, and that the spreading-chamber exposes a much greater cooling-surface to the milk than the entire inner surface of the can, and, at the same time, leaves it all exposed to the

air, and allows the free escape of the gases or of animal odor.

The can can also be filled with milk, as full as transportation will allow, and the cooler can then be inserted, and cool the entire contents of the can in a very short time.

The spreading-chamber can be supplied with water from a reservoir or hydrant above, by substituting a funnel-shaped vessel at the top of tube B, as represented by the dotted lines.

The spreading-chamber could be made in other forms; for instance, coiled or serpentine, of which

Figure 3 shows a cross-section, but the circular is far better; or it may be made flat, as shown in Figure 4.

1. I claim the air-tight spreading-chamber and feeding and discharging-pipes F G, the whole operating as a siphon, for conducting the cooling-liquid through and discharging it from the can, or other vessel containing the liquid to be cooled, automatically.

2. I claim the spreading-chamber, in combination with the tube B and milk-can or vessel as set forth.

Witnesses: MERRITT F. POTTER.

FRANCIS STIFFLE,

HENRY PALMER.
